(57) **CLAIM**

We claim the ornamental design for an electric oven range, as shown and described.

DESCRIPTION

FIG. 1 is a perspective view of an electric oven range showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The structural features depicted by broken lines in the drawings have been shown for the purpose of illustrating portions of the claimed electric oven range that form no part of the claimed design.
